UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,835, dated December 4, 1894.

Application filed October 29, 1894. Serial No. 527,355. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or other woven fabric is clearly illustrated in the accompanying drawing.

• The essential feature of the design is the arrangement and composition of the wide and narrow stripes alternating with each other on a plain back ground, the wide stripes having dark supplemental stripes at each side.

5 G is the wide stripe.

H is the narrow stripe and I is the back ground.

The wide stripe G has a tinted center g, a heavy stripe g' at each side separated from the center by a very thin narrow stripe g^2 and

beyond each dark stripe are the tinted stripes g^3 . Separating the wide stripe from the back ground is a narrow stripe g^4 .

The narrow stripe H consists of a series of light stripes h and dark stripes h' and tinted 25 stripes h^2 , as clearly illustrated in the accompanying drawing.

The narrow stripes alternate with the wide stripes as shown:

I claim—

The design for woven fabric as herein described and clearly shown in the accompanying drawing.

In testimony whereof I have signed my name to this specification in the presence of 35 two subscribing witnesses.

JOHN B. MORGAN.
